Frank Douglas

United States Patent Office.

FRANK DOUGLAS, OF NORWICH, CONNECTICUT.

Letters Patent No. 70,702, dated November 12, 1867.

IMPROVED BLIND-STAPLE.

The Schedule referred to in these Letters Patent and making part of the same.

TO ALL WHOM IT MAY CONCERN:

Be it known that I, FRANK DOUGLAS, of Norwich, in the county of New London, and State of Connecticut, have invented a new and improved Blind-Staple for connecting blind-slats to the rods which guide and govern their position, and for which staples I desire to obtain Letters Patent, as for a new manufacture; and the following is a full, clear, and exact description of the form of said staple, and the mode of construction, which will be more fully understood by reference to the accompanying drawings, which form a part of this specification.

The nature of my invention consists in the production of a vendible article, of a new and highly-convenient and useful shape, and for the purpose of holding blind-slats to the rod in such a way that they hold their relative position to each other and from each other, when shut or opened by the rod which moves and controls them.

Said staples are constructed in such shape that a sharp point is produced for insertion into the wood, and so corrugated that when driven into the wood they cannot easily be drawn out. They can also be made in large quantities by machinery, and kept in the market as an article of merchandise. In the drawings—

Figure 1 represents an edge-view; staple A showing the corrugations, with staple B hanging into it, showing a side view.

Figure 2 represents staples C and D bent, and as they look before being corrugated.

As the wire passes into the machine, for the manufacture of staples, it is cut off in the required lengths for staples, and on an angle, as represented by *ee*, staple C, fig. 2. It is then bent U-shape, as seen at C D, fig. 2. It is then passed between corrugated rollers or dies fitting into each other, in such a manner as to produce the corrugated staples, as represented in fig. 1. In process of corrugating, the straight sides of points *ee*, fig. 2, are bent over to correspond with the cut angles on the opposite sides, so as to form a true and sharp flat point, as represented by fig. 1.

This staple can be easily driven into the wood by machinery, without previously pricking or making a hole, and the grain of the wood is parted as it enters, and closes into the corrugations, which will prevent its being drawn out easily.

While this staple possesses all the advantages of the barbed staple, it possesses the advantage of not being weakened by deep barbs or grooves across the wire. In my staple the whole strength of the wire remains, while a sharp and easy cutting point is made by the sharp angle of the cut and the bent position of the point is to make it central and true.

Claim.

I do not claim as my invention a barbed staple, as that was patented by Byran Boardman, of Norwich, Connecticut, March 30, 1858, but what I claim as my invention, and desire to secure by Letters Patent, is—

As a new article of manufacture, a blind-staple of corrugated wire, as herein described.
